EVAPORATOR UNIT

Filed Feb. 20, 1933

UNITED STATES PATENT OFFICE

2,395,839

EVAPORATOR UNIT

John H. Benson, Salem, Ohio, assignor to Mullins Manufacturing Corporation, Salem, Ohio, a corporation of New York

Application February 20, 1933, Serial No. 657,491

3 Claims. (Cl. 62—126)

This invention relates to an evaporator unit of the sheet metal type, and has to do particularly with sheet metal evaporators such as disclosed in Reissue Patent No. 18,182 of September 8, 1931, as adapted for high side floats or regulators.

The evaporator of the present invention is well adapted to be fabricated from either two sheets or a single folded sheet of metal, and it is an object of the present invention to materially reduce the size of the header by providing a plurality of smaller headers and thus greatly increase the flexibility of the construction to make possible narrower widths and greater use for the entire sharp freezing chamber.

A further object of the invention resides in the eliminating of the cupped ends of the header and thus materially reducing gas welding operations and allowing seam welding around the entire periphery. Distortion sometimes caused by gas welding is also eliminated.

Another object of the invention resides in the provision of relatively small headers to offer greater resistance to bursting pressure; the headers are preferably formed by contiguous portions of the sheets forming the evaporator, with the result that the spaces between the headers may vary considerably.

Other features of design, construction, and arrangement will be more clearly set forth in the specification and claims.

In the drawing:

Fig. 1 is a front elevation of a sheet metal evaporator embodying the present invention.

Fig. 2 is a longitudinal sectional view taken on line 2—2 of Fig. 3.

Fig. 3 is a plan view of the structure shown in Fig. 1, illustrating particularly the spaced apart headers and the connecting T therefor.

Fig. 4 is an enlarged sectional view taken on line 4—4 of Fig. 3.

Fig. 5 is a fragmentary, partly elevational, partly sectional, view of a modified form of seam welded evaporator with a single main header.

Fig. 6 is a longitudinal sectional view taken on line 6—6 of Fig. 5, illustrating the fabrication and seam welding of the ends of the header.

Fig. 7 is a fragmentary plan view taken on line 7—7 of Fig. 6, showing a portion of the header and a portion of one side wall.

The present invention is particularly applicable to sheet metal evaporators of the type disclosed in Booth Reissue Patent No. 18,182, wherein the evaporator is formed of two sheets of metal which are fitted together, welded, and then bent to

shape. In the embodiment of the invention illustrated in Figs. 1 to 4, the evaporator is shown as consisting of headers 2 and 3, the upper embossed portions 4 and 5 of the headers being formed in the outer shell of the evaporator which may be generally designated 6, and the lower embossed portions 7 and 8 of the headers being formed in an inner shell which may be generally designated 9.

A plurality of corrugations 10 are formed in the outer shell 6 and extend from the headers 2 and 3 to a common bottom header 11. If desired, cross manifolds 12 may be formed to the outer shell parallel to and spaced a short distance from the bottom header 11.

Both the outer shell 6 and the inner shell 9 are preferably fabricated from single flat sheets of metal. In fabricating the flat outer sheet, the arcuate portions 4 and 5, the upper portion of a connecting T 13 between the headers, the corrugations 10, the bottom header 11, and the manifolds 12 are all formed from the flat sheet in one stamping operation. The spacing of the headers 2 and 3 from the edges 14 may vary considerably, but the connecting T 13 is fabricated to take care of any such variation.

Likewise the lower portions 7 and 8 of the headers 2 and 3 are formed in the inner shell while still in a flat sheet, and are spaced a corresponding distance from the ends 14 of the inner shell. An important feature to be noted here is that the entire wall sections forming the headers 2, 3, 11 and the manifolds 12 are embossed in the flat inner or outer sheets with the result that no portion of the surface of the headers or manifolds are welded. This makes for an unusually strong wall structure at the point where strength is most needed. After the embossed but flat inner and outer shells 6 and 9 are brought into registry with each other, the two shells are seam welded around their entire periphery, both ends and the sides being completely seam welded so as to seal the space between the two shells, seam welding taking place at the points marked 15.

While still in the flat, the two sheets are reinforced intermediate the seam welded periphery by spot or stitch welding in between the corrugations 10, starting at the headers 2 and 3 and preferably continuing to the manifolds 12 and also between the manifolds 12 and the header 11. After the inner and outer sheets have been welded together by seam welding and spot or stitch welding, the two sheets may then be bent to the desired shape to form an evaporator.

It will be obvious that either a high and nar-

row or a short and wide evaporator may be fabricated from the same flat sheets, and that various contours may also be formed. The ends of the seam welded sheets may or may not be welded at the points 14 and, as best shown in Fig. 3, openings 16 are preferably formed in the top wall.

Fig. 4 is an enlarged view well illustrating the manner of connecting together the headers 2 and 3 by the T unit 13. The main portion of this T is preferably fabricated directly from the sheets 6 and 9 and a common outlet nipple 17 forms the connecting means for completing the T unit 13. One end of the header 11, as formed by the inner shell 9, is preferably enlarged as at 18 to receive an inlet plug 19.

The evaporator is particularly well suited for use with a high side float, capillary tubes and the like, and hence the provision of the inlet 19 in communication with the lower header 11.

In the modification illustrated in Figs. 5 to 7, a larger single header 20 is formed from one piece inner and outer sheets 21 and 22. The header 20 is closed at the ends which permits of complete seam welding around the periphery of the two sheets, while still in the flat, in the same manner as described in connection with the preferred disclosure shown in Figs. 1 to 4. In addition to the header 20, cross manifolds 23 are formed parallel to and closely adjacent the header. The seam welding, spot welding and general fabrication of the evaporator, shown in Figs. 5 to 7, is the same as disclosed in connection with the evaporator shown in Fig. 1, with the exception that the welded flat sheets are initially in the position illustrated in Fig. 6 of the reissue patent of Booth No. 18,182, and such side walls are bent to form the sharp freezing chamber by bending the walls downwardly about suitable dies and then preferably joining the same together along a line directly below the header.

It will thus be seen that I have provided an evaporator of the sheet metal two-piece type which is extremely simple, compact, highly resistant to internal pressure and relatively cheap to fabricate and assemble. Cupped ends are completely eliminated and the complete unit sealed and welded in one continuous operation by simply allowing seam welders to run around the entire periphery, unobstructed by any breaks in the boiler. There is substantially no limit to the narrowness or, for that matter, to the width, of the evaporator and likewise the length of the connecting T 13 between the headers can be varied considerably. The connecting members at the top of the evaporator, between the spaces 16, may be of a length comparable to the length of the T 13 so as to take the form of fixed spacers to prevent the freezing chambers from warping or distorting during the welding, enameling, and annealing operations.

What I claim is:

1. A sheet metal evaporator comprising an outer one piece shell and an inner one piece shell bent to form the side and bottom walls of a sharp freezing chamber, arcuate depressions formed parallel to and spaced from the ends of one of said shells and also spaced from the front and back edges of said shell, said arcuate depressions cooperating with the other shell to form headers located at the ends of the shells but adjacent each

other due to the bent form of the evaporator, embossed portions formed in one shell and cooperating with the other to form conduits extending around the side and bottom walls of the evaporator and connecting the two headers, said shells being welded together around the front and back peripheries and across the end peripheries, said arcuate depressions being dimensioned to form headers each of cross sectional area slightly greater than the individual embossed conduits, and a connecting T forming a common refrigerant conduit between said two headers, a portion of this connecting T being embossed directly from a portion of the sheets between the two spaced headers.

2. A sheet metal evaporator comprising an outer one piece shell and an inner one piece shell bent to form the side and bottom walls of a sharp freezing chamber, arcuate depressions formed parallel to and spaced from the ends of one of said shells and also spaced from the front and back edges of said shell, said arcuate depressions cooperating with the other shell to form headers located at the ends of the shells but adjacent each other due to the bent form of the evaporator, embossed portions formed in one shell and cooperating with the other to form conduits extending around the side and bottom walls of the evaporator and connecting the two headers, said shells being welded together around the front and back peripheries and across the end peripheries, said arcuate depressions being dimensioned to form headers each of cross sectional area slightly greater than the individual embossed conduits, and a connecting T forming a common refrigerant conduit between said two headers, a portion of this connecting T being embossed directly from a portion of the sheets between the two spaced headers, the greater portion of said headers being located outside the sharp freezing chamber defined by the front periphery of the inner one piece shell.

3. A sheet metal evaporator comprising an outer one piece shell and an inner one piece shell bent to form the side and bottom walls of a sharp freezing chamber, arcuate depressions formed parallel to and spaced from the ends of one of said shells and also spaced from the front and back edges of said shell, said arcuate depressions cooperating with the other shell to form headers located at the ends of the shells but adjacent each other due to the bent form of the evaporator, embossed portions formed in one shell and cooperating with the other to form conduits extending around the side and bottom walls of the evaporator and connecting the two headers, said shells being welded together around the front and back peripheries and across the end peripheries, said arcuate depressions being dimensioned to form headers each of cross sectional area slightly greater than the individual embossed conduits, and a connecting T forming a common refrigerant conduit between said two headers, a portion of this connecting T being embossed directly from a portion of the sheets between the two spaced headers, the greater portion of said headers being formed by arcuate depressions in the outer one piece shell.

JOHN H. BENSON.
